[57] CLAIM

The ornamental design for a swimsuit, as shown and described.

DESCRIPTION

FIG. 1 is a front elevational view of a swimsuit showing my new design;

FIG. 2 is a rear elevational view thereof;

FIG. 3 is a right side elevational view thereof; and

FIG. 4 is a left side elevational view thereof.

The broken line showing of a human figure is for illustrative purposes only.
